COMBINED BOTTLE AND BASE THEREFOR

Robert J. Donoghue, Windsor, and Bjorn Bagn, New Hartford, Conn., assignors to Emhart Corporation, Bloomfield, Conn.

Filed July 24, 1970, Ser. No. 24,114

Term of patent 14 years

Int. Cl. D9—01

U.S. Cl. D9—12

FIG. 1

FIG. 4

FIG. 2

FIG. 5

FIG. 3

FIG. 1 is a top plan view of a combined bottle and base therefor, showing our new design;

FIG. 2 is a side elevational view;

FIG. 3 is a bottom plan view;

FIG. 4 is an enlarged, fragmentary sectional view taken through the base and lower portion of the bottle; and

FIG. 5 is an enlarged, fragmentary sectional view taken on the line 5—5 of FIG. 1.

We claim:

The ornamental design for a combined bottle and base therefor, as shown.
